UNITED STATES PATENT OFFICE.

ALEXANDER W. CADMAN, OF STERRETT, ALLEGHENY COUNTY, PA.

GAS-REGULATOR.

SPECIFICATION forming part of Letters Patent No. 329,011, dated October 27, 1885.

Application filed August 3, 1885. Serial No. 173,337. (No model.)

To all whom it may concern:

Be it known that I, ALEXANDER W. CADMAN, of Sterrett township, in the county of Allegheny and State of Pennsylvania, have invented a new and useful Improvement in Gas-Regulators; and I do hereby declare the following to be a full, clear, and exact description thereof, reference being had to the accompanying drawings, forming a part of this specification, in which—

Figure 1 is a side elevation of my improved regulator, the tank and its foundation being shown in vertical section. Fig. 2 is an end view thereof, looking in the direction of the arrow *a*. Fig. 3 is a vertical cross-section of the valves 2 and 3 of Fig. 1. Fig. 4 is a horizontal section on the line *x x* of Fig. 3.

Like letters and figures of reference indicate like parts in each.

40 In the drawings, 4 is a gas-regulator tank of ordinary construction which is mounted upon a vertical pipe, 5, as a standard, upon which it is movable vertically in either direction within certain limits. A tubular sheath or casing, 6, is arranged axially within the tank 4, and projects through the top thereof, to which it is also suitably secured. This sheath encircles the standard-pipe 5, and serves the purpose of steadyng the tank as it moves up and down thereon, and of preventing the escape of gas. The tank 4 is open at the bottom, and is surrounded by the ordinary water-filled tank, 7. The standard 5 is hollow, and communicates at its top, above the tank 4, with a gas-supply pipe, 8, and at the bottom, within the tank 7, is reflexed the vertical recurrent arm 5^a, re-entering the tank 4, and terminating therein above the level of the water. (See Fig. 1.) The gas enters the tank through the standard 5, thereby causing it to perform a double function, which I have found to be of remarkable practical utility.

Just back of the connection of the pipe 5 with the supply-pipe 8 the latter is provided with a regulating valve or cock, 2, the stem of which projects laterally, and is connected by a system of levers or other mechanical devices with the tank 4, in such manner that as the tank rises and falls it will impart a positive rotary motion to the valve. The last lever of the system is pivoted to the tank at a point, *b*.

The construction of the valve 2 is shown in detail in Figs. 3 and 4, which I will explain more fully hereinafter. Suffice it to say for the present that when the tank is at its lowest position, when the pivot will be at the point *b'*, Fig. 1, the falling of the tank will have moved the levers so as to have closed the valve 2, that when the tank rises the valve 60 will gradually open until the pivot *b* reaches the point *b*², when the valve will be opened to its fullest extent, and that as it rises from the point *b*² the valve will gradually close until it reaches its highest point, *b*³, when the valve 65 will be completely shut off. During the downward motion of the tank from the point *b*² to *b'* a reverse series of operations will take place, the valve continuing to open from *b*³ to *b*² and closing from *b*² to *b'*.

Back of the valve 2 the supply-pipe 8 is provided with a valve or cock, 3, to the stem of which is affixed a projecting lever, 10. This lever is joined by a chain, 11, or other flexible connection to the end of one of the levers, 9, 75 which forms part of the system connecting the valve 2 with the tank 4. The chain end of the lever falls with the rise of the tank, and is elevated by its descent, and as the tank falls will exert a tension on the chain 11, and will 80 turn the valve 3 to close it. If the tank be allowed to descend to its lowest position, *b'*, it will shut the valve 3 to close it entirely. After that the rise of the tank, while it will operate the valve 2, would have no effect on the valve 85 3, by reason of its flexible connection. Depression of the lever 10 opens the valve.

A by-pass or pipe, 12, of small diameter relatively to the supply-pipe 8, enters the latter back of the valve 3, and extends in a 90 line preferably parallel with the supply-pipe to a point forward of the valve 2, where it re-enters the pipe. The by-pass is provided with a cut-off valve, 13, the projecting lever 14 of which rests upon the inner end of the 95 lever 9, which rises and falls with the tank, or it may be prolonged and rest directly upon the surface of the tank itself. The effect of motion of the tank on the valve 13 is to close it by raising the lever 14. The descent of the 100 tank has no effect on the valve.

Forward of the valve 2, and preferably opposite to the entrance of pipe 5, is a short vertical pipe, 15, in which is a common push

safety-valve, the elevation of whose stem allows gas to escape through a waste-pipe, 16. The valve-lever 17, which operates the safety-valve has its fulcrum at 18, and has two arms, one 5 of which rests upon the projecting stem of the valve, and is provided with a counter-weight, 19, suspended from the lever by a vertical rod, 20. The other arm is connected with the surface of the moving tank by a flexible chain, 21. If the tank should fall to its lowest position, b' , it will draw the chain 21 taut and move the lever 17 so as to release the stem of the safety-valve, which will then open and permit free egress of gas from the supply-pipe 15 and tank through the waste-pipe 16. The counter-weight 19 is situated at a proper distance from the surface of the tank 4, so that the ascent of the latter to a level near its highest limit will raise the counter-weight, and by 20 thus relieving the lever 17 of pressure will open the safety-valve and give a free escape for the gas.

Thus constructed, suppose the gas-tank to be in a position somewhat above its lowest 25 level, with the center b between the points b' and b^2 , and the valves 2, 3, and 13 all open. The gas then entering the supply-pipe 8 at its adit 8^a will traverse it in the direction of the arrow c , passing through the valves 3 and 2, and 30 thence through the continuation 8^b of the pipe to the furnace-burners or other place of utilization. During its course the gas has free access to the tank 4 through the pipe 5 5^a , and any increase or diminution of pressure will 35 immediately be made apparent by a corresponding rise or fall of the tank. Suppose that the pressure of the gas should suddenly increase, by reason of those intermittent gushes so common in the distribution of natural gas. 40 The tank will then rise, and until the intermediate point, b' , is reached will open the valve 2 wider. On passing this point the motion of the system of connecting-levers 22 9 24 23 will gradually close the valves 2 and 13, and 45 correspondingly lessen the amount of entering gas until an equilibrium is established between the gas-pressure and the gravity of the tank, when the latter will come to rest. If, however, the gush should be very excessive 50 and sudden, the tank will rise far enough to close the valves 2 and 13 and to shut off the supply of gas entirely. It will at the same time raise the counter-weight 19 and cause the gas to escape through the waste-pipe 16. The 55 object of the latter action is to relieve the tank from the great pressure and to prevent the impetus thereof from raising it too far. During the period in which the valves 2 and 13 are shut the furnaces are fed by the reserve 60 gas contained in the tank, and as soon as enough is removed to relieve the pressure the tank begins to fall and opens the valve 2 and closes the safety-valve. During all this time 65 an almost perfect equality of pressure will have been maintained. Suppose, on the other hand, that the tank is between the levels b^3 and b^2 , and that the pressure of gas is dimin-

ished: the gravity of the tank will cause it to fall, and in falling to move the levers to open the valve. If the diminution of pressure be 70 not too great, the opening of the valve will restore equilibrium and bring the tank to rest. If, however, the diminution be great, as if it be caused by shutting off the gas-supply, the tank will descend below the level b^2 , and in its further descent to the point b' will close the valve 2 completely. The motion of the lever 9 necessary to close this valve will raise the hand-lever 10 and will shut the valve 3. All 75 gas is then cut off from the tank, (if the latter 80 has in its operations risen far enough to close the small valve 13,) and the supply to the burners will cease altogether. The motion of the tank to the level b' will tighten the chain 21 and will open the safety-valve, thereby allowing any accumulation of low-pressure gas in the tank or supply-pipes to escape harmlessly through the pipe 16, and not into the combustion-chamber. Another function of the safety-valve is that when the tank falls 85 and opens it any leaking gas from the closed valves 2 and 3 will be discharged into the open air.

In case the supply of gas should be cut off altogether, the proper mode of operation is to 90 shut off the burner-valves and to throw the valve 13 open. Then when the supply recommences a small amount of it will pass from the pipe 8 through the by-pass 12, and again into the pipe 8 forward of the valve 3. 95 When sufficient pressure of gas comes, it will raise the tank 4, open the valve 2, and cut off the safety-valve. The workman can then open the valve 3 with his hand and start the tank 100 into regular operation, as before described.

The function of the valve 3 is to prevent a 105 too sudden income of gas. With the tank-regulators now in common use the gas often enters at first with such a rush as to throw the tank violently upward, and to cause serious injury to its mechanism. In my regulator, however, when the tank has descended, the gas is first admitted through the pipe 12, and is not allowed to enter at full pressure 110 until the tank has risen far enough to shut or 115 nearly shut the valve 2, when the valve 3 is opened by hand.

The peculiar function of the pipe 12 is to 120 enable the tank to be filled without opening the larger valve 3. It is not used, and is ordinarily kept closed, except for filling the tank at the beginning of the operations of the regulator. If for any reason it should become desirable to be able to dispense with the use of the regulating tank, a by-pass pipe, 25, may 125 be fitted to the supply-pipe 8 back of the entrance of the pipe 12, and made to re-enter the pipe 8 at a point forward of the tank-pipe fittings. By means of this by-pass the gas may be led to the burners without at all affecting the tank. A valve, 26, serves to cut off this by-pass or to open it, as desired.

The internal construction of the valve 2 is yet to be described. The supply-pipe 8 has

its adit into the valve at a port, 28, and its exit is at the other side thereof at 29. The exit-port is closed by a tapering conical valve seat or shell, 30, through the outer side of 5 which, and opening into the port 29, is a hole or port, 29'. A conical valve, 31, open at the top and bottom, fits within the seat 30, and has two oppositely-situate lateral ports, 32, in its shell. If the valve be turned by its stem 10 33 to bring either one of the ports 32 opposite the exit-port of the seat, the gas will pass freely from the adit through the hollow valve 31 and out of the exit-port 29 into the supply-pipe. A quarter-revolution of the stem 15 33 will separate the ports of the valve and its seat, and will cut off the flow of gas through the supply-pipe, while a semi-revolution of the stem will bring the other port 32 opposite the port of the valve-seat, and will re-establish 20 free flow of gas therethrough. At intermediate points the ports will be partly in conjunction and a partial flow of gas maintained.

Thus constructed, the valve is connected with the gas-tank by the compound system of 25 levers shown in Fig. 1, which are so related that a movement of the tank from b' to b^2 will give the valve-stem 33 a quarter-turn and will open the valve, while the movement from b^2 to b^3 will also give a quarter-turn and close 30 the valve. I do not, however, desire to limit myself to the form of valve just described, since many other forms possessing the same property of opening and closing will answer the purpose. Nor do I desire to limit myself 35 to the use of levers as a connecting mechanism between the tank and the valve 2, although it is preferable, because of its certain positive movement. In other respects a rack and pinion and other kinds of connections are equivalents. If this valve be used as the stop-valve 40 3, its connecting mechanism should be so arranged that the fall of the tank will give it the necessary quarter-turn to close it.

It will be noticed that the regulator-valve 45 and its mechanism are situate above the level of the top of the gas-tank. This is important, because it renders the valve easy of access, and prevents leakage of gas from doing any harm.

50 What I claim as my invention, and desire to secure by Letters Patent, is—

1. The combination, in a gas-regulator, of a regulating-tank capable of rising and falling with the increase or diminution of gas-pressure, a gas-supply pipe having a discharge into 55 the tank, a valve in the gas-supply pipe, whose stem is connected with the tank and capable of operation by the movements thereof, the valve and connecting mechanism being so arranged that at the complete descent of the tank the valve will be closed, that it will be open when the tank is in an intermediate position, and that when the tank has completely risen the valve will be closed, substantially as 60 and for the purposes described.

2. The combination, in a gas-regulator, of a regulating-tank capable of rising and falling

with the increase or diminution of gas-pressure, a gas-supply pipe having a discharge into 70 the tank, a valve in the gas-supply pipe, whose stem is connected with the tank and capable of operation by the movements thereof, the valve and connecting mechanism being so arranged that at the complete descent of the tank the valve will be closed, that it will be open when the tank is in an intermediate position, and that when the tank has completely risen the valve will be closed, and an auxiliary 75 valve, 3, for opening and closing the supply-pipe, said auxiliary valve being so connected 80 with the tank as to be closed by the full descent thereof, substantially as and for the purposes described.

3. The combination, in a gas-regulator, of a regulating tank capable of rising and falling 85 with the increase or diminution of gas-pressure, a gas-supply pipe having a discharge into the tank, a valve in the gas-supply pipe, whose stem is connected with the tank by rigid connecting mechanism, so as to be capable of a 90 positive operation by the movements thereof, the valve and connecting mechanism being so arranged that at the complete descent of the tank the valve will be closed, that it will be open when the tank is in an intermediate position, and that when the tank has completely risen the valve will be closed, substantially as 95 and for the purposes described.

4. The combination, in a gas-regulator, of a regulating-tank capable of rising and falling 100 with the increase or diminution of gas-pressure, a gas-supply pipe having a discharge into the tank, a valve in the gas-supply pipe, whose stem is connected with the tank and capable of operation by the movements thereof, a by-pass pipe, 12, leading from the supply-pipe at a point back of the valve, and re-entering 105 the same at a point forward of the valve, and a valve for opening and closing the by-pass pipe, substantially as and for the purposes described. 110

5. The combination, in a gas-regulator, of a regulating-tank capable of rising and falling with the increase or diminution of gas-pressure, a gas-supply pipe having a discharge into 115 the tank, a valve in the gas-supply pipe, whose stem is connected with the tank and capable of operation by the movements thereof, a by-pass pipe, 12, leading from the supply-pipe at a point back of the valve, and re-entering 120 the same at a point forward of the valve, and a valve for opening and closing the by-pass pipe, the last-named valve being connected with the tank, so as to be closed by the rise thereof, substantially as and for the purposes 125 described.

6. The combination, in a gas-regulator, of a regulating-tank capable of rising and falling with the increase or diminution of gas-pressure, a gas-supply pipe having a discharge into 130 the tank, a valve in the gas-supply pipe, whose stem is connected with the tank and capable of operation by the movements thereof, the valve and connecting mechanism being so ar-

ranged that at the complete descent of the tank the valve will be closed, that it will be open when the tank is in an intermediate position, and that when the tank has completely risen the valve will be closed, an auxiliary valve for opening and closing the supply-pipe, said auxiliary valve being so connected with the tank as to be closed by the full descent thereof, a by-pass pipe, 12, leading from the supply-pipe at a point back of the first-named valve and the auxiliary valve, and re-entering the pipe forward of both thereof, and a valve for opening and closing the by-pass pipe, substantially as and for the purposes described.

15 7. The combination, in a gas-regulator, of a regulating-tank capable of rising and falling with the increase or diminution of gas-pressure, a gas-supply pipe having a discharge into the tank, a valve in the gas-supply pipe, whose stem is connected with the tank and capable of operation by the movements thereof, the valve and connecting mechanism being so arranged that at the complete descent of the tank the valve will be closed, and a safety-

20 25 valve whose adit-pipe communicates with the tank, and the supply-pipe, and whose lever is connected with the tank, so that the safety-valve will be opened by the complete descent thereof, substantially as and for the purposes described.

30 8. The combination, in a gas-regulator, of a regulating-tank capable of rising and falling with the increase or diminution of gas-pressure, a gas-supply pipe having a discharge into the tank, a valve in the gas-supply pipe, whose stem is connected with the tank and capable of operation by the movements thereof, the valve and connecting mechanism being so arranged that at the complete de-

scent of the tank the valve will be closed, that it will be open when the tank is in an intermediate position, and that when the tank has completely risen the valve will be closed, and a safety-valve whose adit-pipe communicates with the tank and the supply-pipe, and whose lever is connected with the tank, so that the safety-valve will be opened by the complete descent thereof, said lever having a counter-weight situate in the path of the tank, for opening the safety-valve when the tank approaches its highest point, substantially as and for the purposes described.

9. The combination, with a rising and falling gas-tank, 4, movable vertically within a water-filled tank of the nature described, of a vertical hollow standard, 5, which traverses the tank 4, and on which the latter moves, said standard being connected with a gas-supply pipe, and having a re-entrant arm, 5^a, which opens into the tank 4, above the level of the water therein, for the purpose of enabling the standard to perform the double function of a gas-supply pipe and a standard, substantially as and for the purposes described.

10. The combination of a gas-regulating tank of the nature described, and a valve for regulating the supply of gas to the tank, and operated automatically by the movements thereof, said valve being situate above the level of the top of the tank, substantially as and for the purposes described.

In testimony whereof I have hereunto set my hand this 25th day of July, A. D. 1885.
